UNITED STATES PATENT OFFICE.

ANDREW L. HATFIELD, OF NEWARK, NEW JERSEY, ASSIGNOR TO HYFIELD MANUFACTURING COMPANY, A CORPORATION OF NEW YORK.

GRINDING-MACHINE.

1,176,895.

Specification of Letters Patent.

Patented Mar. 28, 1916.

Application filed May 4, 1915. Serial No. 25,691.

To all whom it may concern:

Be it known that I, ANDREW L. HATFIELD, a citizen of the United States, and a resident of Newark, in the county of Essex and State 5 of New Jersey, have invented certain new and useful Improvements in Grinding-Machines, of which the following is a specification.

The objects of this invention are to provide a grinding machine which can be used by barbers or the like for grinding their various tools to sharpen the same; to provide a single machine specially adapted to grind various tools or instruments; to secure an 10 improved construction enabling each kind of blade to be ground readily and with great facility; to secure compactness and reduction of number of parts; to provide a horizontal grinding surface mounted upon a 15 table adapted to rotate about a vertical axis; to admit readily stopping said table from rotating and starting the same; to secure simplicity of construction and operation, and to obtain other advantages and results as 20 may be brought out in the following description.

Referring to the accompanying drawings, in which like numerals of reference indicate the same parts throughout the several views, 25 Figure 1 is a plan view of a machine embodying my invention; Fig. 2 is an elevation of the same looking at the end nearest the bottom of the sheet in Fig. 1; Fig. 3 is a transverse sectional view on line A—A of Fig. 1, and Fig. 4 is a perspective view of a cam lever for raising the table.

In the specific embodiment of the invention illustrated in said drawings, the reference numeral 1 indicates a base upon which 30 the various parts are mounted. Carried at the front corner of the base is a vertically disposed pedestal 2 providing a central bore 3 adapted to receive the stem 4 of a table 5. Preferably the table is disk shape with its 35 stem 4 extending therefrom whereby the table may be caused to rotate in a plane substantially parallel to the base. At the top of said table is provided a grinding surface which may be formed integral with said 40 table or separately as may be found most convenient or desirable. As shown in the drawings said grinding surface is formed separable from the table, and comprises a disk 6 of substantially the same diameter as 45 the table and of any suitable material adapted to the purpose. Projecting upwardly from the table eccentric to the center thereof, is a pin 7 adapted to be received in a pocket 8 in the disk 6 whereby the disk and table may be caused to rotate together. By 50 this construction it will be obvious that as the grinding surface becomes worn, it may be replaced, or where it is desired to substitute disks providing grinding surfaces having greater or less abrasive qualities, the 55 same may be done with ease and at small cost.

Preferably the periphery of the table 5 is beveled toward its under side, as at 9, and engages at one side of the pedestal with a 55 friction drive wheel 10. Said drive wheel is shown arranged in a plane perpendicular to the plane of the table and has its periphery beveled to correspond with the beveled periphery of said table, and may be 60 caused to rotate continuously by any suitable means such as the motor 11 shown.

In operation, when it is desired to place a blade, as for instance a blade such as used in clippers which has to be laid flat upon the 65 grinding surface so as not to round the edges, it is preferable to place said blade upon the grinding surface when the same is standing still. In order to do this, the table is adapted to be raised so as not to engage 70 the drive wheel 10, and consequently will stand still at such time. The blade is then placed upon the grinding surface and held there as the table is lowered and again rotates. As shown in the drawings, the stem 75 4 is long enough and of uniform diameter within the pedestal so as to provide an adequate bearing surface and allow the table to be raised and lowered without any material wobbling. The under side of the table is 80 preferably a smooth or polished surface so that the operator can easily and safely lift the same with his fingers while it is rotating. For greater safety, however, a cam 39 is 85 pivoted as at 40 to the pedestal adapted 90 when swung to raise the table. It will be noted from the drawings that the table in its lowered position is supported by engagement with the friction drive wheel 10, the weight 95 of the table and pressure exerted by the operator upon the blade being sufficient to obtain an efficient and positive drive.

The friction drive wheel 10 is mounted

upon one reduced end 12 of a horizontal shaft 13 supported in separated arms 14, 14 of a standard 15. Upon the shaft 13 between the arms 14, 14 is a drive pulley 16 5 preferably as wide as the space between said arms and secured to said shaft so that the same is prevented from longitudinal movement. Between the arm 14 and the friction wheel 10, is a sleeve 17 and upon the opposite side of the friction wheel 10 is a nut 18 10 adapted to clamp the friction wheel against the shoulder formed by the difference in diameter of the shaft. The opposite end of the shaft 13 projects beyond the standard 15 and is reduced and carries non-rotatably 15 thereon a grinding cylinder or roll 19. Above the shaft 13 and parallel therewith is another shaft 20 rotatably mounted in the arms 14, 14 and reduced at its opposite ends 20 beyond said arms. At its end overlying the grinding roll 19 the same carries a similar roll 21, and at its opposite end is arranged a grinding wheel 22. Between the arms 14, 14 and upon said shaft is a pulley 23. A 25 belt 24 extends from said pulley to a corresponding pulley 25 on the motor 11. The same pulley 25, may be utilized for driving both of said pulleys 16 and 23 on the parallel shaft 13, 20 the belt 26 on the first of said 30 shafts being crossed so as to rotate said shafts in opposite directions.

Preferably the grinding cylinders are separated so as to admit applying alternately thereto a razor blade for sharpening 35 the same. In order to support a blade and apply it to the rolls, a lateral extension 27 is provided on the arm 14 of the standard toward said rolls, said extension being arranged midway between the grinding roll 28, and 40 shafts 13, 20 and perpendicular to the common plane of said shafts. Said extension is longitudinally recessed and adapted to receive a rod or blade holder support 28, and is also provided with set screws 29 45 for holding said rod in any adjusted position. At a distance from the end of the extension, said rod is bent at substantially right angles to itself and extends parallel, as at 30, to the grinding rolls 19, 21. Slidably supported by this parallel portion 30 of the rod 28, is a suitable blade holder 31 50 adapted to be rocked up and down on said parallel portion so as to alternately present the blade to the opposite rolls. The operator may both rock the blade holder and move it longitudinally of the portion 30 of the rod 28 while grinding the blade so as to present the same to different portions of the rolls and grind it evenly upon both 55 sides, and when the blade is sufficiently ground the blade holder may be slid entirely off of the end of the rod 28 and the blade exchanged for another. It will be noted that the end of the rod 28 terminates sufficiently 60 beyond the plane of the ends of the grinding 65

roll so that the blade holder 31 may be placed upon the rod before the blade enters at all between the grinding rolls.

For holding work in proper relation to the grinding wheel 22, a work support 32 70 is provided adjacent the periphery thereof, said work support being vertically adjustable and adapted to be twisted and adjusted to any desired position and angle. As shown in the drawings the work support 32 75 provides a work holding member 33 having a cylindrical stem 34 carried in a corresponding recess of a transverse member 35. Said transverse member also provides a cylindrical stem 36 carried in a horizontal member 80 37 also having a cylindrical stem 38 and supported by the arm 14 of the standard 15 next the grinding wheel. It will be noted that the stem 38 of this last or horizontal member 37 is perpendicular to the plane 85 of the shafts 13, 20; that the transverse horizontal members 35, 38 are in substantially the same plane and at right angles to each other; and that the transverse member 35 and the work holding member 33 are in 90 a common plane and at right angles to each other. Since the stems of all the said members are round and admit turning one member with respect to the other, and since all of said members are adjustably slid able, a 95 great range of adjustability of the work support is afforded, it being understood that suitable clamping means are provided for preventing inadvertent movement of said members when adjusted.

Obviously detail modifications and changes may be made in the manufacture of my improved grinding machine without departing from the spirit and scope of the invention, and I do not wish to be understood 105 as limiting myself except as required by the following claims when construed in the light of the prior art.

Having thus described the invention, what I claim is,

1. In a grinding machine, the combination with a shaft and means for driving the same, of a drive wheel on said shaft, a rotatable grinding table engaging said drive wheel, and means for supporting said grinding table so that movement in a direction perpendicular to it will engage it with or disengage it from said drive wheel.
2. In a grinding machine, the combination with a shaft and means for driving the same, of a drive wheel on said shaft, a grinding table mounted to rotate upon a vertical axis and adapted to engage said drive wheel by gravity, and means for supporting said grinding table so that axial movement thereof will engage it with or disengage it from said drive wheel.
3. In a grinding machine, the combination with a horizontal shaft and means for driving the same, of a drive wheel on said

shaft having its periphery beveled, a grinding table having a beveled periphery adapted to engage the beveled periphery of said wheel, and means for supporting said grinding table so that movement in a direction perpendicular to it will engage it with or disengage it from said drive wheel.

4. In a grinding machine, the combination with a shaft and means for driving the same, of a drive wheel on said shaft, a rotatable grinding table engaging said drive wheel, a grinding member removably mounted upon said table and mounted to rotate therewith, and means for supporting said grinding table so that movement in a direction perpendicular to it will engage it with or disengage it from said drive wheel.
5. In a grinding machine, the combination with a shaft and means for driving the

same, of a drive wheel on said shaft, a rotatable grinding table engaging said drive wheel, means for supporting said grinding table so that movement in a direction perpendicular to it will engage it with or disengage it from said drive wheel, and means for moving said table to disengage it from said drive wheel.

6. In a grinding machine, the combination with a shaft and means for driving the same, of a drive wheel on said shaft, a rotatable grinding table adapted to interchangeably support one of a plurality of grinding members, and means for supporting said grinding table so that movement in a direction perpendicular to it will engage it with or disengage it from said drive wheel.

ANDREW L. HATFIELD.
